UNITED STATES PATENT OFFICE.

LEWIS B. DOMAN, OF ELBRIDGE, NEW YORK, ASSIGNOR TO AMPHION PIANO PLAYER COMPANY, OF ELBRIDGE, NEW YORK, A CORPORATION OF NEW YORK.

PNEUMATIC SELF-PLAYING MUSICAL INSTRUMENT.

1,141,621.

Specification of Letters Patent.

Patented June 1, 1915.

Original application filed March 9, 1905, Serial No. 249,250. Divided and this application filed November 28, 1908. Serial No. 464,988.

To all whom it may concern:

Be it known that I, LEWIS B. DOMAN, of Elbridge, in the county of Onondaga, in the State of New York, have invented new and useful Improvements in Pneumatic Self-Playing Musical Instruments, of which the following, taken in connection with the accompanying drawings, is a full, clear, and exact description.

10 This invention relates to certain improvements in pneumatic self-playing musical instruments and refers more particularly to the sound producing action involving the use of graded pneumatics forming the subject matter of my pending application No. 249,250, of which the present application is a division.

One of the main objects of the present invention is to grade or vary the capacity of 20 certain sets of the striker pneumatics so as to gradually subdue the tones of the keys corresponding to the striker pneumatics of gradually reduced capacity, or on the other hand to render certain parts of the musical 25 selection more prominent than others. In this particular instance I have shown the striker pneumatics for the bass keys of the piano as gradually reduced in width from right to left and it therefore follows that 30 the areas or capacities of the striker pneumatics for the bass tones are different from those of the higher or treble tones of the scale as particularly pointed out in the original application #249,250 previously referred to.

Other objects and uses related to the construction and relative arrangement of the sound producing action will be brought out in the following description.

40 In the drawings—Figure 1 is a front elevation partly broken away of a pneumatic self-playing musical instrument showing portions of the striker pneumatics as graded or gradually reduced from the right to left 45 of the scale. Fig. 2 is an enlarged transverse sectional view of the same player taken on line 2—2, Fig. 1.

The sound producing action comprises 50 separate series of striker pneumatics —1— and a wind chest —2— in which is mounted a series of primary pneumatics —3— corresponding to the number of striker pneumatics, and a corresponding number of valves —4—, each controlled by its corre-

sponding primary pneumatic —3— to control the action of the corresponding striker pneumatic.

The action of the primary pneumatic is controlled by a perforated music sheet —5— and tracker bar —6— and suitable ducts —7— leading to the primary pneumatics —3— as best seen in Fig. 2.

The wind inducing device comprises a bellows —8— and equalizer —9— which is adapted to be operated by suitable pedals —10— and is connected through the medium of a conduit —11— to the wind chest —2— for maintaining suitable air tension in the wind chest and other parts of the sound producing action in the manner described in my pending application previously referred to.

The striker pneumatics —1— are arranged in groups one above the other and are mounted upon separate supporting shelves —13— and —14—, those of the upper set being connected by flexible tubes —15— to the wind chest while those of the lower set are connected by similar tubes —16— to the same wind chest, the latter being also connected by flexible ducts —7— to the tracker bar so that each set of striker pneumatics and also the wind chest constitute separate units in the structure capable of being removed or replaced and adjusted in position without disturbing either of the other units.

The music sheet —5— is adapted to be wound and unwound from suitable rollers —18— and —19— which are actuated by a suitable motor action —20— and suitable connections between the motor action and rollers similar to that set forth in my application referred to but form no part of my present invention.

The motor action is actuated by the wind inducing device —8— through the medium of a conduit —21— and suitable tempo-governing device —22— which is also fully described in my pending application previously mentioned.

The expression or sound producing action is controlled by an expression governing pneumatic —26— and suitable connections also described in my application referred to but form no part of my present invention.

Aside from the gradation or variation in the relative sizes of the striker pneumatics as described, another feature of my inven-

tion is the division of the parts of the sound producing action into separate and separable units as for example arranging the striker pneumatics in separate sets one above the other upon separate supports and connected to a separate wind chest by flexible connections whereby each unit may be adjusted or replaced independently of the other units.

10 The operation of my invention will now be readily understood upon reference to the foregoing description and accompanying drawings.

What I claim is:

15 1. An auto-pneumatic piano playing device having striker pneumatics varied in area from one part to another part of the scale, those for the bass tones being of less area than those for the treble tones.

20 2. An auto-pneumatic piano playing de-

vice having striker pneumatics varied in width from one part to another part of the scale.

3. In a self-playing musical instrument, a series of striker pneumatics for the bass 25 notes gradually reduced in capacity from right to left.

4. In a self-playing musical instrument, a series of striker pneumatics corresponding to different tones of the instrument, those 30 for the bass tones gradually decreasing in width from right to left in combination with means for controlling the operation of said pneumatics.

In witness whereof I have hereunto set 35 my hand this 21st day of November 1908.

LEWIS B. DOMAN.
